UNITED STATES PATENT OFFICE.

JOHN GRANT, OF LOS ANGELES, CALIFORNIA.

BEAM-HANGER CONSTRUCTION.

Application filed September 21, 1925. Serial No. 57,659.

This invention relates to a well pumping device wherein a walking beam is connected to the rods of a reciprocating well pump. It pertains particularly to a safety device for holding a pump rod in case of breaking of the hanger or parts operatively securing the beam to the polish rod or equivalent portion of the pump string.

It is the primary object of this invention 10 to provide a device of the character described which is simple, economical, durable, does not interfere with the operation of the equipment or require changes in the standard equipment now used.

15 These objects together with other objects and corresponding accomplishments are obtained by means of the embodiment of my invention illustrated in the accompanying drawing, in which:

20 Fig. 1 shows in vertical section my improved hanger construction mounted on the end of a walking beam, a fragment of the latter being shown; and Fig. 2 is a view of the structure shown in Fig. 1.

25 Referring particularly to the drawing, 3 indicates a walking beam which is slotted at the end as indicated by 4, through which slot the stem of a beam hanger may pass. Mounted in a suitable groove extending 30 transversely across the top of the beam is a crown having a cross head 5 provided with an arcuate upper guide 6 overhanging the beam for receiving a cable or like flexible line.

35 A stem 7 depends from the cross head, and at the lower end thereof is a supporting guide 8 of arcuate form for receiving a cable. The polished rod forming a portion of the pump string is indicated by 9 and 40 mounted thereon is a clamp or grip 10. The grip is provided with trunnions on opposite sides, and socket eyes 12 are pivotally mounted thereon. Passed over the guide head 8 and secured to the socket is a cable 13. This 45 cable is intended to couple the polished rod to the beam and to be the operating means for reciprocating the polished rod.

Extending beneath the grip 10 is a safety 50 cross bar 14 having trunnions 15 at the ends thereof. Pivotally mounted upon the trunnions 15 are eye sockets 16 to which a cable 17 is secured. Cable 17 is passed over guide 6. This cable with associated parts is intended to catch the polished rod in the event 55 that the hanger stem or cable breaks. The operation of the structure is obvious.

What I claim is:

1. A beam hanger structure adapted to be supported upon a walking beam comprising an upper cross head provided with a curved cable receiving way, a lower guide head having a curved cable receiving way secured to and spaced below said upper head. 60

2. A beam hanger structure adapted to be supported upon a walking beam comprising an upper cross head provided with a curved cable receiving way, a stem depending therefrom, a lower guide head having a curved cable receiving way secured to said stem so as to be spaced below said upper head. 65

70 3. A beam hanger structure comprising a cross head adapted to rest and ride upon a walking beam and being provided on its upper side with a curved cable receiving way, and a lower cable supporting head secured below said cross head and having an upper curved guideway for a cable. 75

80 4. A beam hanger structure comprising a cross head adapted to rest and ride upon a walking beam and being provided on its upper side with a curved cable receiving way, a stem depending from said cross head, and a lower guide head having a curved cable receiving way secured to said stem so as to be spaced below said upper head. 85

85 5. A beam hanger structure comprising the combination with a walking beam and polished rod having a grip of a beam hanger mounted on said walking beam and having an arcuate upper guide head, a cable passed over said head and secured to said grip for reciprocating the latter, said hanger having a lower arcuate supporting guide head disposed below said upper head, a cable passed over said lower head, and means secured to 90 said last mentioned cable to support said rod upon release of the latter from said mentioned cable. 95

100 6. A beam hanger structure comprising the combination with a walking beam and polished rod having a grip of a beam hanger mounted on said walking beam and having an arcuate guide head, a cable passed over said head and secured to said grip for reciprocating the latter, and auxiliary means 105 anchored to said beam and passing beneath said grip to engage the latter upon release of said rod from said beam hanger.

110 7. A beam hanger structure comprising the combination with a walking beam and polished rod having a grip of a hanger having a cross head pivotally supported upon

said beam and having a crown providing an arcuate guide for a cable, a stem depending from said hanger and having an arcuate supporting guide for a cable at the bottom thereof, a cable passed over said last mentioned guide and secured to said grip, safety means disposed below said grip and about said polished rod for engagement with said

grip, and a cable passed over said crown guide and secured to said safety means so as to support said rod upon release of said grip from said hanger.

In witness that I claim the foregoing I have hereunto subscribed my name this 8th day of September, 1925.

JOHN GRANT.
